UNITED STATES PATENT OFFICE.

SAMUEL J. BENS, OF NEW YORK, N. Y.

BABY CARRIAGE.

Application filed September 20, 1924. Serial No. 728,880.

This invention relates to a baby carriage of the type in which the wheels upon which the device is supported are arranged in a tandem fashion, one at the front and one at the rear.

The principal object of my invention is the provision of means whereby a basket or bassinet or seat may be secured to a frame either detachably or otherwise, the frame having means attached thereto whereby a pivoted support or prop may be actuated by certain movements of the basket or otherwise to support the device in upright position.

Other objects and advantages will appear as the description proceeds.

To this end my invention includes a handle-like frame terminating at its lower portions in wheel fixtures to which wheels are applied, one at the front and one at the rear, and a basket or bassinet having a rigid or semi-rigid frame attached to the handle portion above the wheels, with part of the handle above the wheels extending above the bassinet or basket axially thereof. The invention further includes a support pivoted to a fixture carried by the handle member and the frame of the basket or bassinet whereby rotation of the basket or bassinet about its longitudinal axis will cause the support to be rotated about its pivot, so that the entire device will be supported on a base which will include two wheels and the supporting element.

The invention further includes the construction, combination and arrangement of parts shown in the drawings and described hereafter.

I have illustrated in the accompanying drawings one embodiment of the invention, but it is to be understood that I do not wish to be limited thereto as the example illustrated is simply given as required by law to exemplify the principle involved.

In these drawings:

Figure 1 is a side elevation of one embodiment of my invention.

Fig. 2 is an end elevation of Fig. 1 showing the support collapsed.

Fig. 3 is an end elevation of the device of Fig. 1 with the support in opened out position.

Fig. 4 is a plan view of the skeleton framework.

Fig. 5 is a detail.

Fig. 6 is an end elevation showing a modified form of fixture.

Fig. 7 is a side elevation of the device of Fig. 6.

Fig. 8 is a side elevation of a modified form of structure.

Fig. 9 is a detail of the supporting means shown in Fig. 8.

Referring now with particularity to the embodiment illustrated, I have shown a handle or frame member 1 to which is applied a fork element having a socket portion 2 adapted to receive the end of the handle 1 and legs 3 diverging outwardly from the socket 2 adapted to receive an axle 4 which carries a wheel 5. A similar arrangement of parts is provided at the other end of the handle 1 so that a tandem arrangement of wheels exists, one tracking behind the other in the plane of the handle portion.

A bassinet or basket is shown at 6 fastened or otherwise secured to a frame which is separated at its ends, thus forming segments 7^a and 7^b. A fixture 8 bridges the gap between the ends of segments 7^a and 7^b and is secured to said segments as by means of bolts 9 and 10 respectively. A bolt 11 penetrates the handle member 1 and the fixture 8 and a nut 12 placed on the end thereof secures the bassinet to the frame in a pivotal manner. It will be noted that the bassinet in its frame is mounted eccentrically in the handle portion 1, that is, the preponderance of weight of the basket is to one side of the bolt 11.

The fixture 8 is provided with a depending finger portion 13 extending downwardly between the right angular lugs 14 of the supporting fixture 15. This latter element consists of a plate deformed around three sides of the handle element. The lugs 14 are integral with one side of this plate, and that part of the plate on the opposite side of the handle 1 is of substantially triangular shape as shown at 17. Both the parts 13 and 17 of the support fixture are provided with aligning apertures which are adapted to receive a bolt 18 which passes through the handle member 1 so that this fixture is secured thereto in a pivotal manner.

A ground engaging supporting rod is shown at 19 which has a depending bent portion 20 adjacent each wheel which is adapted to engage the ground and support the entire device in a manner which will be more fully described hereinafter. Beyond the bent portion 20, the supporting rod extends upwardly in substantially parallelism

with the lower portion of the handle 1. The uppermost portion of the supporting rod passes inside of the offset portion 21 formed in a support fixture 15, wherein it is secured by welding, brazing or otherwise. Within this offset portion 21 a kink 22 or bent out part is provided which will engage the side of the handle 1 and limit the movement of the supporting rod 19 toward the wheel 5. Upward movement of the supporting rod 19 about the bolt 18 as its pivot is limited by reason of the fact that the upper extremity of the rod 19 or the top surface of the support fixture 15 will engage the side of the handle when the support is moved outwardly from the wheel.

It will now be apparent that pressure upon the segments 7^a of the bassinet frame will cause, through the depending finger 13, movement of the support fixture 15, as the finger 13 is held between outwardly projected lugs 14 on this fixture. Therefore, such movement causes a partial rotation of the support 19 about its pivot 18 or in a direction away from the wheel 5. This movement is continued until the ground engaging loops 20 of the support 19 are sufficiently far removed from the two wheels 5 to provide a rigid support for the vehicle. It will also be noted that by moving the upper portion of the handle 1 in the same direction as the direction of movement of the ground engaging support 20, while the above operation is being carried out, that the bassinet frame will remain substantially parallel to the ground and level throughout this operation.

It will also be noted that by reason of the fact that the bassinet is eccentrically mounted, that is, that the preponderance of weight is on the same side of the handle as the support 19, that this weight will tend to keep the support 19 close up against the wheel, or so that the part 22 will always remain in contact with the handle 1. This prevents the support from sticking out from the wheel and interfering with the progress of the vehicle.

It may be found desirable instead of having the bassinet frame segmental, to make this integral as is shown at 25. In this case hooks 26 would be secured to the bassinet and a fixture 27 secured to the handle in a pivotal manner by means of bolt 28. It would also be found desirable to provide depressions in the fixture 27, one side of which would have a straight wall 29, the other an undercut wall 30, the minimum distance between the walls 29 and the other side of the depression being less than that part of the hook 26 seated therein. Such a construction would make necessary the jockeying of the hook into the depression, so that it would not be accidentally removed therefrom.

By utilizing such a construction as above and providing feet 31 on the bassinet, the entire basket might be lifted from the running gear and used as a crib for a young child.

The bolts 9 and 10 allow the segments 7^a and 7^b to be rotated about these parts as a pivot when it is desired to fold the entire device so that it will occupy a space of minimum thickness, such for instance, when it is desired to place the entire device in a suit case or trunk. It will also be seen from the nature of the fixture 8 that the base thereof supports the segments 7^a and 7^b in any other outward position.

It will now be apparent that I have provided a device for transportation of young children or packages which will occupy a position close to the side of the one carrying the same, which has but two wheels, so that a minimum amount of space is required, yet which may be readily left in an upright position without being supported by the operator by reason of the pivot support secured to the handle, which normally occupies the position against the wheels and out of the way.

As a further modification it may be desirable to provide a seat-like structure between the vertical portions of the handle element 1, when a child of three or four desires to use the device as a self propelled car. Such a structure is shown to consist of a seat member 33 supported from hangers 34. These hangers are provided at their uppermost portions with hooks 35 which are adapted to seat in the grooves or indentations in the pivoted fixture as used with the detachable bassinet. In order to keep the seat member from swinging about the fixture pivot, I may provide elongated hooks 36 pivoted to the fixture as at 37, and having their bent ends 38 adapted to pass through apertures 39 in the handle 1, so that rotation of the fixture about its pivot will be prevented.

Not only may this device then be used by a child for propelling itself by sitting on the seat 33 and grasping the handle bars 40, but if desired, the parent or adult with the child may grasp the handle 1 above the child's head, while the child places its feet upon the intermediate support 41 carrying the seat 33. In this way propulsion and guidance is taken from the hands of the child and placed in the hands of the supervising adult.

I claim:

1. A device of the character described, including a basket or seat adapted to receive a small child, a frame for said basket or seat, a handle for the device, said frame being pivoted to said handle, wheels adapted to track one behind the other and secured to the handle, and a pivoted support for the

device adapted to be moved outwardly away from the wheels so that the device is supported by the wheels and the ground engaging element.

5. 2. A device of the character described including a basket having a frame, a handle, tandem wheels arranged in the plane of the handle, said basket frame being mounted for pivotal movement, a pivoted ground engaging element, and means for causing movement of the ground engaging element about its pivot by movement of the basket frame.

10. 3. A device of the character described including a basket having a frame, a handle therefor, wheels for the device arranged in the plane of the handle, said basket being pivoted to the handle out of the longitudinal axis of the basket, a ground engaging element secured in a fixture and pivoted to the handle, and means carried by the basket frame, engaging the ground engaging fixture for causing pivotal movement of the ground engaging support.

15. 4. A device of the character described including a basket, a frame therefor, a handle for the device, tandem wheels arranged in the plane of the handle, said basket frame being segmental, a fixture joining the separated ends of the basket frame in a pivotal manner, said fixture being secured pivotally to said handle, a ground engaging support carried by a fixture, also mounted pivotally on said handle, and means on the basket frame fixture for engaging the ground engaging fixture so that movement of one segment of the basket frame will cause movement of the ground engaging element away from the wheel.

20. 5. A device of the character described, including a handle, a body supporting element pivotally hung from said handle, and a wheel carried by each end of said handle, and means cooperating with said wheels to support the device in upright position, said means being actuated by pivotal movement of the body supporting element.

25. 6. A device of the character described, including a handle, a body supporting element pivotally hung from said handle, a wheel carried by each end of said handle, and means cooperating with said wheels to support the device in upright position, comprising a ground engaging support pivoted to the handle at each end of the body supporting element normally occupying a position out of contact with the ground, and adjacent said wheels, pivotal movement of said body supporting element moving said support away from said wheels.

30. 7. A device of the character described, including a handle, a body supporting element between the ends of said handle, a fixture

pivotedly connecting one end of said body supporting element and said handle, a depending finger on said fixture, a support pivoted to said handle, said finger engaging said support.

35. 8. A device of the character described, including a handle, a body supporting element pivotally hung from said handle, a wheel carried by each end of said handle adapted to track one behind the other, and means cooperating with said wheels to support the device in upright position, comprising a ground engaging support pivoted to the handle at each end of the body supporting element normally occupying a position out of contact with the ground, and adjacent said wheels.

40. 9. A device of the character described, including a handle, a body supporting element pivotally thereto, wheels carried by said handle, a ground engaging element pivoted to said handle and means for causing movement of said ground engaging element about its pivot by movement of the body supporting element about its pivot.

45. 10. A device of the character described including a substantially semi-circular rigid handle having downwardly extending portions, a wheel carried at each end thereof, an elliptical frame pivoted to and carried between the downwardly extending portions of said handle, said frame carrying a body supporting bassinet, said frame and bassinet being above said wheels, a ground engaging element pivoted to said handle, and means in said frame engaging the ground supporting element holding the latter in inoperative position.

50. 11. A device of the character described, including a substantially semi-circular rigid handle having a wheel at each end thereof, a body supporting element pivoted to said handle, a ground engaging element pivoted to said handle, and means on said body supporting element engaging said ground engaging element holding the latter in inoperative position.

55. 12. A device of the character described, including a substantially rigid handle, a wheel at each end thereof and adapted to track one behind the other, a body supporting element pivotally carried by said handle, a ground engaging element pivoted to said handle, the body supporting element being out of center on said handle, the preponderance of weight thereof being on the same side of the handle as the ground engaging element, and means on said body supporting element engaging the ground engaging element and moving the same.

In testimony whereof, I affix my signature.

SAMUEL J. BENS.
